UNITED STATES PATENT OFFICE.

THOMAS STANLEY PHILPOTT, OF NEWTOWN, NEW ZEALAND.

NON-REFILLABLE BOTTLE.

SPECIFICATION forming part of Letters Patent No. 746,374, dated December 8, 1903.

Application filed December 2, 1901. Serial No. 84,488. (No model.)

To all whom it may concern:

Be it known that I, THOMAS STANLEY PHILPOTT, a subject of His Majesty the King of Great Britain and Ireland, residing at Mein street, Newtown, in the Colony of New Zealand, have invented a new and Improved Non-Refillable Bottle, of which the following is a specification.

The object of this invention is to provide a bottle which can be readily filled in the first instance, but which cannot be refilled except with considerable trouble and difficulty.

The invention consists in fitting the inside of the bottom of the neck with a conical valve-seat, which is normally covered by a ball-valve.

A stopper is fitted into the neck to guide and limit the rise of the ball and is provided with holes or channels for the escape of liquor from the bottle.

20 The stopper is kept in position by a bolt (or a plurality of bolts) projected from the stopper by a spring or springs and taking into a recess or recesses in the neck of the bottle.

In the accompanying drawings, Figure 1 is 25 an elevation of the upper part of a bottle; Fig. 2, a vertical central sectional elevation of the same. Fig. 3 is a transverse section on 3 3, Fig. 1; and Fig. 4, a similar section on 4 4, Fig. 1.

30 The bottle-neck 1 has an internal flange 2 near its junction with the bottle, and upon said flange rests the conical valve-seat 3, tapering upwardly and formed at its upper end to receive the ball-valve 4.

35 The stopper 5 fits the inside of the neck, and its lower end rests upon a flange 6, projecting from valve-seat 3, whereby said valve-seat is retained in position. The stopper has a recess 7 to receive and guide the ball 4, and 40 passages 8 open communication between the recess 7 and a channel 9, formed circumferentially upon the stopper. Passages 10 through the upper part of the stopper permit liquid to pass from said channel 9 to the open neck beyond the stopper when it is desired to withdraw the contents of the bottle.

45 Passages 8 and 10 are not in line with each other, so that there is great difficulty in passing a wire through them in case attempt should 50 be made to hold the ball-valve from its seat in order to refill the bottle.

Bolts 11 and 12 are carried in a hole 13, formed through the stopper at right angles to the neck, said bolts being projected by a coil-

spring 14 into recesses 15 and 16, formed in 55 the neck upon opposite sides of the stopper.

In operation the bottle is first filled in the ordinary way. The valve-seat 3 and the ball-valve are then inserted. The stopper is taken in the hand so that the fingers press the bolts 60 inwardly against the spring and the stopper inserted in the bottle-neck and pushed down until the bolts pass into the recesses.

A cork may be forced into the top of the neck in the usual manner. 65

The whole of the parts, except the spring, can be made of glass, porcelain, or other similar material.

What I claim as my invention, and desire to secure by Letters Patent, is— 70

1. In a non-refillable bottle a flange upon the internal circumference of the neck, a valve-seat resting thereon, a stopper fitting the neck and engaging at its lower end a flange projecting from the valve-seat, a ball 75 received by a recess in the stopper, an opening in the valve-seat closable by the ball, the stopper having a circumferential channel and passages giving communication between said channel and said recess and the upper 80 part of the stopper having passages from said channel to the open neck of the bottle and means for securing the stopper within the bottle-neck.

2. In a non-refillable bottle a flange upon 85 the internal circumference of the neck, a conical valve-seat resting thereon a stopper fitting the neck and engaging at its lower end a flange projecting from the valve-seat a ball received by a recess in the stopper and adapted to close an opening in the valve-seat, the stopper having a circumferential channel and 90 passages giving communication between said channel and said recess and the upper part of the stopper having passages from said channel to the open neck of the bottle the stopper having a hole transversely through it, bolts 95 within said hole projecting in opposite directions and a spring between the bolts; the neck of the bottle having recesses to receive the 100 ends of said bolts.

In witness whereof I have hereunto set my hand in presence of two witnesses.

THOMAS STANLEY PHILPOTT.
